UNITED STATES PATENT OFFICE.

MENDEL OSNOS, OF BERLIN, GERMANY, ASSIGNOR TO GENERAL ELECTRIC COMPANY,
A CORPORATION OF NEW YORK.

SYSTEM FOR PRODUCING HIGH-FREQUENCY OSCILLATIONS.

1,173,679.

Specification of Letters Patent. Patented Feb. 29, 1916.

Application filed February 3, 1914. Serial No. 816,191.

To all whom it may concern:

Be it known that I, MENDEL OSNOS, a subject of the Czar of Russia, residing at Berlin, Germany, have invented certain new 5 and useful Improvements in Systems for Producing High-Frequency Oscillations, of which the following is a specification.

My invention relates to systems for producing high frequency oscillations, and more 10 particularly to an arrangement of the transmitting mechanism forming a part thereof.

In the production of high frequency oscillations for use in systems of radio communication or similar installations, it is, of 15 course, highly desirable to work without excessive danger to the apparatus and without excessive wear. Such installations use motor-generator sets for the production of high frequency currents, and various difficulties 20 have been encountered with the arrangements used for causing the oscillations. When the work circuit from the alternating current machine is broken or short circuited by the operating key, certain high voltages 25 or heavy currents are set up which may readily do harm to the apparatus. The short circuiting currents will be especially large if the machine has an air gap of normal or large size. Further, such voltages 30 and currents necessarily cause a sparking at the operating key which soon destroys its contacts. Similarly, if the operating key be used to short circuit the shunt field of the generator, the high inductance of this field 35 will give rise to excessive sparking at the contacts of the key. Accordingly, I propose, by my invention, to provide such an arrangement of the transmitting apparatus 40 in a system for producing high frequency oscillations, that its operation will be attended with as little danger as possible, and that satisfactory operation will be had without excessive wear on the apparatus involved. To attain these results I provide 45 the alternator which supplies energy to such a system with a field winding of low inductance, preferably excited from the mains of the driving motor and arranged in series with said motor, and connect the operating key as a short circuit around this field winding. When this short circuit is altered the increased flux on the machine will produce 50 a voltage sufficient to jump the spark gap and cause an oscillation. In the preferred form of my invention I also supply the

alternator with a second field winding for furnishing part of the excitation.

In the accompanying drawing the single figure shows diagrammatically the circuit of a transmitting apparatus of a wireless 60 telegraph station arranged according to my invention.

In general, the transmitting apparatus shown comprises a motor-generator set 1 supplied with power from the direct current 65 mains 2, and furnishing high frequency alternating current to the work circuit 3.

The showing of the work circuit 3 is wholly diagrammatic and is intended to be typical of that in common use for wireless 70 telegraphy, as any arrangement of this circuit may be used in a system embodying my invention. For this purpose I have indicated the alternating current generator as connected to the primary of a step-up transformer 10 whose secondary is connected to the primary of a step-up transformer 11. Interposed in the latter circuit is the usual 75 spark gap 12, while a condenser 13 is bridged across the secondary of the transformer 10. One terminal of the secondary of the transformer 11 is shown as connected to ground at 14, while its other terminal is connected to a circuit 15 leading to suitable 80 antennæ.

The motor-generator set 1 comprises a direct current motor 20 having a shunt field winding 21 and supplied with power from the direct current mains 2. A high frequency alternator with armature winding 22 is driven by this motor. The alternator has two field windings 23 and 24, the former being in shunt across the mains 2, while the latter is a low inductance winding which may be placed in series with the 95 motor. In circuit with the field winding 23 is a suitable rheostat 25.

In shunt with the series field winding 24 I provide an operating key 30. As will be 100 seen by an inspection of the drawing, this key is normally closed and forms a short circuit around the series field winding. When the key is depressed against the action of the spring this short circuit will be 105 removed.

The operation of my arrangement will be as follows:—The rheostat 25 will first be so adjusted that the excitation of the field winding 23 will produce such a voltage in the armature 22 that after transformation at 110

10 it will not be quite enough to cause a spark across the gap 12. It will then be seen that when the operating key 30 is depressed the series field winding 24 will give 5 an added excitation for the alternator. This will be sufficient to raise the voltage so that it will jump the gap 12 and produce an oscillation at the antennæ. The key being released, the series field winding 24 will be 10 again short circuited and the voltage of the alternator decreased. By such an arrangement I am enabled to obtain the results desired. Since the series field winding supplies only a portion of the excitation, it need 15 have but a comparatively small number of turns and hence will be of small inductance. Because of the inherent characteristics of a series winding, its inductance will be small whether it be used alone or in conjunction 20 with a second winding. Consequently, the sparking at the contacts of the operating key will be reduced to a minimum. Further, since we are neither opening nor short circuiting the work or armature circuit, the 25 alternator will not be endangered.

Although I have described herein the best embodiment of the invention now known to me, I do not wish to be limited to the exact details shown, but seek to cover in the appended claims all those modifications which come within the scope and spirit of my invention.

What I claim as new and desire to secure by Letters Patent of the United States, is:—
35 1. A wireless signaling system including an antenna, means operatively related to said antenna for producing high frequency oscillations, said means comprising an alternating current generator, a direct current 40 motor for driving the same, said generator having a field winding in series with its motor, and means for varying the voltage delivered by said generator to induce electrical oscillations in said antenna in accordance with the signals to be transmitted,

comprising means for opening and closing a short circuit around said series field winding.

2. A wireless signaling system including an antenna, means operatively related to said antenna for producing high frequency oscillations, said means comprising an alternating current generator and a direct current motor for driving the same, the generator being provided with two field windings, one of 50 said field windings being connected in series with said motor, and the other field winding being excited from a constant potential source, and means for quickly varying the flux produced by said series field winding 55 to thereby vary the voltage of said machine and induce an electrical oscillation in said antenna.

3. A system for producing high frequency oscillations, including a transmitting mechanism, said mechanism comprising an alternating current generator, a direct current motor for driving the same, the generator having a field winding connected in shunt relation to said motor and another field 60 winding connected in series with said motor, and means for quickly varying the flux produced by said series field winding.

4. A system for producing high frequency oscillations, including a transmitting mechanism, said mechanism comprising an alternating current generator, a direct current motor for driving the same, the generator having a field winding connected in shunt relation to said motor and another field 70 winding connected in series with said motor, and means for short circuiting said series field winding.

In witness whereof, I have hereunto set my hand this 16th day of January, 1914.

MENDEL OSNOS.
